Primary Examiner—Ruth McInroy*Assistant Examiner*—Terrence Huang(74) *Attorney, Agent, or Firm*—Flynn, Thiel, Boutell & Tanis, P.C.(57) **CLAIM**

The ornamental design for a retaining ring for shaft, as shown and described.

DESCRIPTION

FIG. 1 is a front view for the retaining ring for shaft showing our new design, the rear view being a mirror image;

FIG. 2 is a top view thereof;

FIG. 3 is a bottom view thereof;

FIG. 4 is a left side view thereof, the right side view being a mirror image;

FIG. 5 is a sectional view taken along line 5—5 in FIG. 1 thereof;

FIG. 6 is a front view thereof, the retaining ring mounted on a shaft; and,

FIG. 7 is a side sectional view thereof, the retaining ring and a bearing mounted on a shaft.

The broken lines showing in FIGS. 6—7 are for illustrative purposes only and form no part of the claimed design.
